DESIGN FOR A COMBINED SALT AND PEPPER SHAKER OR THE LIKE

Ralph H. Holmes, Hartington, Nebr.

Application April 1, 1939, Serial No. 83,980

Term of patent 14 years

To all whom it may concern:

Be it known that I, Ralph H. Holmes, a citizen of the United States, residing at Hartington, in the county of Cedar and State of Nebraska, have invented a new, original and ornamental Design for Combined Salt and Pepper Shaker or the like, of which the following is a specification, reference being had to the accompanying drawing, forming part thereof.

Figure 1 is a front perspective view of a combined salt and pepper shaker or the like, showing my new design.

The rear of the article is plain.

I claim:

The ornamental design for a combined salt and pepper shaker or the like, as shown and described.

RALPH H. HOLMES.
